UNITED STATES PATENT OFFICE

1,940,149

RAZOR

Hyman R. Segal, New York, N. Y., assignor to
Segal Founders Corporation, a corporation of
New York

Application May 27, 1931. Serial No. 540,230

7 Claims. (Cl. 30—12)

This invention relates to a functionally and structurally improved razor which may be efficiently employed to give a satisfactory shave and in which the parts may be cleaned readily 5 and the blade expeditiously removed when desired.

It is an object of the invention to provide an article of this character by means of which the parts may readily be adjusted and shifted from open to closed positions.

Moreover, by the present invention, a structure is presented which will prevent to the greatest extent a clogging of the parts despite the fact that they may be freely subjected to immersion in lather and other careless handling without being 15 subsequently thoroughly cleaned.

Among other objects of the invention are those that provide a razor embodying relatively few parts, each individually simple and rugged in construction, and capable of production largely by 20 automatic machinery and assemblage by unskilled labor, these parts operating over long periods of time with freedom from difficulty.

With these and other objects in mind, reference is had to the attached sheet of drawings 25 illustrating practical embodiments of the invention and in which:

Fig. 1 is a fragmentary partly sectional side view of the razor in closed condition;

Fig. 2 is a similar view showing the razor in 30 open condition;

Fig. 3 is a sectional view of the lower portion of the razor and

Figs. 4 and 5 are views similar to Figs. 1 and 3, but showing a slightly different form of 35 construction.

In these views numeral 5 indicates a clamping plate for cooperation with a guard 6. Between these elements, a blade (not shown) is to be interposed. This blade is preferably maintained 40 upon the guard by a blade-positioning lug or abutment 7, forming a part of the latter. The clamping plate is pivotally supported upon the upper end of a stem 8 and this stem extends within the bore of a tube 9 of which the guard forms an 45 integral or fixed part. The stem carries a pin 10 which, as shown at 11 in Figure 3, may be spring-pressed. This pin projects through a slot 12 formed in the tube 9 and extends beyond the same to ride within a spiral slot 13 formed in a 50 sleeve 14. The latter is rotatably supported upon the tube and is maintained against displacement at one end as, for example, by a retaining ring 15 and at the other end rotatably bears against a knob 16 fixedly secured to the tube.

Thus, it will be obvious that, as the tube is ro-

tated with respect to the sleeve, the pin will traverse the slot 13 and in so doing, will ride upwardly within the slot 12 from the position shown in Figure 1 to the position shown in Figure 2. Also, due to the fact that the upper end of the 60 slot 12 is tangentially offset as at 17, the final movement of the parts incident to this shifting will cause the stem and clamping plate carried thereby to rotate axially as in Figure 2. Consequently, a blade having a proper opening, may 65 be freely withdrawn over the clamping plate and from a position on the guard.

In the form of construction shown in Figure 4, the sleeve is formed with a groove 18 rather than a slot 13. Consequently, the sleeve surface will 70 not be broken as is the case in the structure of Figures 1 to 3. As shown, it is preferred that the slot 18 be formed in a separate cylindrical member 19 rather than in the inner face of the sleeve. Otherwise, the sleeve-stock might have to 75 be too heavy. If such a construction is resorted to, the cylindrical member may be grooved or slotted and thereafter simply driven home within the sleeve in such manner that relative movements between these elements are prevented. Ad- 80 jacent the upper end of the slot 18 the sleeve may be formed with an opening 20 through which an implement may be introduced in order to effect a retraction of the pin 10. In certain respects the structure illustrated in Figs. 4 and 5 is pre- 85 ferred and it will be apparent that with this lay-out of apparatus the operator by simply gripping the sleeve and turning the knob with respect thereto, may, by one continuous movement cause, first, a projection of the stem, second, a turning 90 thereof, together with the clamping plate carried thereby and, third, a rocking of the clamping plate to the position shown in Fig. 2.

It will be noted that the slots 13 and 18 have their lower ends offset as at 21 so that proper 95 adjustment may be secured without the parts accidentally shifting with respect to each other. As a consequence, the parts may be seated and thereafter by a relatively minute amount of turning of the knob with respect to the sleeve, 100 the blade may be flexed to just the extent desired.

In the form of construction shown in Figs. 4 and 5, the sleeve may extend up to the guard member. Consequently, the entrance of water, 105 soap, etc., into the interior of the razor is prevented to the greatest extent. The ring 15 in the form of construction as shown in Fig. 1 will also serve to prevent the entrance of foreign agents. If it is desired to disassemble the parts, 110

this may be accomplished readily by simply re-tracting or otherwise removing the pin 10 and detaching the knob. Thereupon, the various parts may be withdrawn. In lieu of the ring 15 5 as shown in Fig. 1, the tube as in Fig. 2 may be extended as at 22 to provide a structure whereby entrance of soap is prevented.

Thus, among others, the several objects of the invention as specifically aforementioned are achieved. 10 It will be appreciated that numerous changes in construction and rearrangement of the parts might be resorted to without departing from the spirit of the invention as defined by the claims.

Having described my invention, what I claim 15 as new, and desire to secure by Letters Patent is:

1. A razor, comprising a stem, a knob secured thereto, a tube enclosing said stem, a sleeve associated with said tube, a guard secured to said tube, a clamping plate secured to said stem, 20 means for retaining said sleeve in position with respect to said tube, and means whereby said clamping plate is caused to shift axially and rotatably with respect to said guard to permit of a blade being dismounted from the latter.

25 2. A razor, comprising a stem, a knob secured thereto, a tube enclosing said stem, a sleeve associated with said tube, a guard secured to said tube, a clamping plate secured to said stem, means for retaining said sleeve in position with 30 respect to said tube, said sleeve being rotatable with respect to said tube and knob, and means functioning automatically upon such relative rotation occurring to shift said clamping plate axially and rotatably away from and towards 35 said guard.

3. A razor, comprising a stem, a knob secured thereto, a tube enclosing said stem, a sleeve associated with said tube, a guard secured to said tube, a clamping plate secured to said stem, 40 means for retaining said sleeve in position with respect to said tube, said sleeve being rotatable with respect to said tube and knob, and means associated with said stem, tube and sleeve whereby, upon the latter being rotated with respect to 45 said tube, said clamping plate will be shifted

axially and rotatably away from and towards said guard.

4. A razor, comprising a clamping plate and guard, a tube secured to said guard, a stem mounted on said plate, a sleeve enclosing said tube, said tube and sleeve being each formed with track ways, a pin carried by said stem and cooperating with said track ways, and at least one of the latter being spirally disposed whereby relative rotation of said sleeve and tube will cause longitudinal shifting of said stem and plate with respect to said guard. 80

5. A razor, comprising a clamping plate and guard, a tube secured to said guard, a stem mounted on said plate, a sleeve enclosing said tube, said tube and sleeve being each formed with slots and a pin carried by said stem and extending through said slots, one of said slots being tangentially disposed whereby relative rotation between said sleeve and tube will cause longitudinal shifting of said stem and plate with respect to said guard. 85

6. A razor, comprising a clamping plate and guard, a tube secured to said guard, a stem mounted on said plate, a sleeve enclosing said tube, said tube being formed with a slot, said sleeve being formed with a groove in its inner face, a pin carried by said stem and extending through said slot into said groove, whereby relative rotation of said tube with respect to said sleeve will cause longitudinal shifting of said stem and plate with respect to said guard. 95

7. A razor including a tube, a sleeve, a cylindrical member interposed between said sleeve and tube and fixed against movement with respect to the former, said member and tube being formed with slots, a stem slidably disposed within said tube, a clamping plate carried by said stem, a guard secured to said tube, and means connected to said stem and extending through said slots at the point of intersection thereof to shift said stem longitudinally of said tube as said sleeve and member are rotated with respect to said tube. 100
